UNITED STATES PATENT OFFICE.

GAIL BORDEN DOBSON, OF LOS ANGELES, CALIFORNIA.

VALVE-STEM SILENCER.

Application filed February 23, 1921. Serial No. 447,015.

To all whom it may concern:

Be it known that I, GAIL BORDEN DOBSON, a citizen of the United States, residing at Los Angeles, in the county of Los Angeles 5 and State of California, have invented new and useful Improvements in Valve-Stem Silencers, and the following is such a full, clear, and exact disclosure of the invention that anyone skilled in the art to which it 10 appertains may make and use the same.

My invention comprises a valve silencer for internal combustion engines, and embodies a device adapted to be interposed between the top of the valve stem, of a valve 15 of the poppet type, and the valve stem actuating end of the rocker arm, to absorb the shock and eliminate the noise resulting from sharp contact between these parts, during operation of the motor.

20 My principal object is to provide a simple and inexpensive device of this character, applicable to motors of standard construction, which will effectually eliminate the noise of valve operation.

25 Specifically, it consists of a sleeve member slidably mounted on the upper end of the valve stem, and held yieldingly in contact with the valve actuating end of the rocker arm; and a member, formed of sound deadening material, retained within and by the 30 sleeve, to serve as a cushion between the contacting faces of the valve stem and the rocker arm.

In addition to eliminating the noise resulting from this valve actuation by the 35 rocker arm, the device serves to hold the push rod in contact with its actuating cam, at all times; and also the rocker arm is such contact with the push rod, that any 40 looseness in the connections between these parts will be taken up, and the consequent noise resulting therefrom eliminated.

I have illustrated the preferred specific 45 form of my invention in the accompanying drawings, and a full disclosure of its construction and operation will be found in the following specification, wherein reference is made to the drawings.

In the drawings, Fig. 1 is a transverse section through a typical internal combustion 50 motor, showing a valve and its actuating mechanism, and my invention as applied thereto; Fig. 2 is an enlarged fragmentary transverse vertical section through the valve 55 of Fig. 1, showing it in closed position and the relative position of the rocker arm;

Fig. 3 is a view similar to Fig. 2, showing the valve in open position as actuated by the rocker arm; Fig. 4 is a further enlarged fragmentary sectional view, taken as indicated by the line 4-4 of Fig. 2, showing in detail the relative positions of the upper end of the valve stem, and the contact end of the rocker arm when the valve is closed; and Fig. 5 is a view similar to Fig. 4, taken 60 as indicated by the line 5-5 of Fig. 3, showing the relative positions of the upper end of the valve stem and the contact end of the rocker arm, when the valve is opened 65 thereby.

70 While I have stated that my present invention is particularly applicable to use as a means for eliminating the clicking noises resulting from the rocker arm method of valve actuation in internal combustion motors; and the following specification and accompanying drawings illustrating it are each drawn to illuminate such use and application; it is nevertheless to be understood that the device is not necessarily limited to 75 such a restricted application, but may be utilized in other fields, with equal success, where similar objects are to be accomplished.

80 Referring now to the drawings the numeral 10 designates generally a typical internal combustion motor, having a cylinder 11 in the top of which is operatively mounted a valve of the poppet type, and generally designated by the numeral 12.

85 The valve 12 comprises a head or valve portion 13 and a stem 14 formed integral therewith, the latter being slidably mounted in a suitable bearing 15 in the top of the cylinder 11; the head 13 being adapted to normally rest in a seat 16, likewise formed in the top of the cylinder 11. The valve portion 13 is held normally seated in the seat 16, by the action of an expansile coil spring 17, surrounding the stem 14, and confined 90 between the top of the outer cylinder wall 18 and a seat 19, mounted on the upper end of the stem 14. The valve spring seat 19 here shown is typical of the type commonly 95 used on motors of this character, and comprises a cup-shaped portion 20 having a concentric aperture through its bottom 24, through which the upper end of the valve stem extends; and an annular flange 21, extending outwardly from the upper rim of the cup-shaped portion 20, forming the annular seat 22 in which the upper end of the 100

110

spring 17 rests. The seat 19 is retained on the upper end of the valve stem 14 by means of a pin 23, extending through a transverse aperture in the stem against which pin the bottom 24 of the cup-shaped portion 20 abuts.

As is usual in motors of this type of construction, the valve is held normally seated by the action of the spring 17, and is actuated in its opening movement through the medium of a rocker arm 25, pivotally mounted, as at 26, on a suitable standard or support 27 on the top of the cylinder block 11, this rocker arm being actuated or oscillated through the medium of a push rod 29, the upper end 29^b of which engages the end 28, and the lower end 29^a of which is engaged by a suitable cam 30 rigidly mounted on a cam shaft 31. The cam shaft 31 is rotated in the usual manner through the medium of spur gears 32 and 33, driven from the main crank shaft 34 of the motor. Thus it will be seen that rotation of the cam 30, and contacting with the end 29^a of the push rack 29, will raise the end 28 of the rocker arm 25, causing it to oscillate upon its pivot 26, moving the end 35 downwardly and into contact with the upper end of the valve stem 14, to unseat the valve 13 against the action of the spring 17.

In order that the valve portion 13 will seat perfectly in the seat 16, it is usual in motors of this type of construction, when the valve is closed, as shown in Fig. 1, for the contact face 36 of the end 35, of the rocker arm 25, to be slightly spaced from the top face 37 of the stem 14, and to accomplish this it is generally necessary to have the push-rod 29 pivotally connected, by a pin or other means, to the end 28 of the rocker arm 25, and a coil spring (not shown) in connection with the push rod 29, to hold it downwardly with its end 29^a in constant contact with the cam 30. To eliminate noise and too much lost motion the space between the faces 36 and 37 is ordinarily very slight, generally no more than the thickness of a sheet of letter paper, which space is very difficult to maintain in proper adjustment, owing to the constant wearing of parts, expansion due to heat, and from other causes.

With the use of my device, as will later appear, the space between the faces 36 and 37 can be made a great deal larger than in ordinary practice, thereby obviating the necessity of frequent adjustments to maintain the slight space above mentioned, obviating the necessity of a pivotal pin connection between the pin 28 and the upper end of the push-rod 29, and also permits the elimination of the aforementioned spring on the push rod 29 to hold the lower end 29^a in contact with the cam 30. Not only can the last mentioned structural features be eliminated, but the allowance of a large space be-

tween the faces 36 and 37 will obviate the possibility of the valve portion 13 improperly seating in the seat 16 due to any slight derangement in the adjustment of the push rod 29 and the rocker arm 25.

My invention comprises essentially the sleeve 38 slidably mounted on the upper end of the valve stem 14, the upper end of which is normally held in contact with the face 36 of the rocker arm 25, by the action of an expansible coil spring 39 confined between the valve spring seat 19, and an annular flange 40 extending outwardly from the upper end of the sleeve 38. The sleeve 38 may be constructed of any suitable material, such as steel, brass, or the like, the portion 38 being of such length as to allow considerable space between the faces 36 and 37, with the upper end or flanged portion 40 remaining in contact with the face 36 at all times, and the sleeve portion 38 extending downwardly below the face 37, so as to prevent its tipping or slipping off the valve stem 14 when the said faces are spaced their greatest distance. Diametrical opposed slots 41 may be cut in the lower end of the sleeve portion 38 so this portion can pass downwardly over the pin 23; however, in some cases the cup-shaped portion 20 may be of sufficient depth to permit the sliding of the sleeve 38 on the stem 14 without coming in contact with the pins 23 in which case the slots 41 can be omitted. The spring 39 may be formed in any desired manner, either to be confined between the bottom 24 of the cup-shaped portion 20, and the flange 40, or as shown in the drawings to rest upon the upper portion of the seat 19, and be confined between this portion and the flanges 40. In any event the spring 39 will be weaker than the valve spring 17.

A shock absorbing and silencing disk 42, constructed of any suitable material such as fibre, rubber, or the like, is retained within and by the sleeve 38, between the contact face 36 of the rocker arm 25 and the top face 37 of the valve stem 14. This disk may be of any suitable thickness to accomplish the purpose of absorbing the shock and eliminating the noise of contact between the faces 36 and 37, when the motor is in operation. The sleeve 38 being in contact with the face 36 of the rocker arm 25 at all times, the disk 42 will be retained within the sleeve and in position at all times to be interposed between the faces 36 and 37 during operation. For this reason the diameter of the disk 42 may be slightly less than that of the inner diameter of the sleeve 38, so that it will normally rest on the face 37. However, it may be of such diameter as to fit the bore of the sleeve closely and be carried by it during its sliding movement on the stem 14. The space between

the faces 36 and 37 will never be great enough that, in case the disk 42 is made smaller than the bore of the sleeve 38, it will become turned up on edge and interfere in any manner with perfect operation of the valve mechanism.

Each and all of the parts, as including the sleeve 38, spring 39 and disk 42, are very simple in construction and very cheap to manufacture; therefore, instead of having to replace valves and rocker arms due to the usual wear caused by contact of the faces 36 and 37, it will only be necessary to replace the sleeve 38 and disk 42, or, in most cases, only necessary to replace the disk 42, thereby reducing to a minimum the cost of maintenance of these parts of the motor.

In actual operation the spring 39 supported on the valve stem 14 and holding the sleeve 38 in contact with the face 36 of the rocker arm 35, will also hold the end 28 in contact with the upper end 29^b of the push rod 29, and also the end 29^a in contact with the cam 30, thereby obviating the necessity of a spring on the push rod 29 to hold the lower end in contact with the cam 30. Also by the exertion of this force on the end 35 of the rocker arm 25 the spring 39 will take up any looseness in the joints of the rocker arm 25 and the push rod 29, thereby eliminating any rattling noises resulting from such looseness, due to wear of the parts, in addition to eliminating the noises resulting from contact between the faces 36 and 37 during operation of the motor. Furthermore, the greater space being permitted between the faces 36 and 37, due to my improved device, the valve portion 13 will be permitted at all times to properly seat in the seat 16, and will not be prevented from properly functioning in this respect, due to any slight inaccuracies of adjustment of the rocker arm 25 and its actuating parts. Where this slight space between the faces 36 and 37 has been heretofore made, to eliminate noises, the valve has been very often prevented from properly closing due entirely to this space being entirely taken up owing to expansion of the parts by heat. With my device it is perfectly clear that these imperfections of operation will be entirely eliminated.

While I have described the preferred specific embodiment of my invention, I reserve to myself the right to make any changes or modifications in structure, which come within the scope of the following claims.

Having described my invention, I claim:

1. In a device of the character described, the combination of a member interposed between the valve stem and its actuating means to deaden the sound of contact therebetween, means mounted independently

movable relative to the valve stem and its actuating means to prevent lateral displacement of said sound deadening member, and means to yieldingly hold said movable member in engagement with said actuating means.

2. In a device of the character described, the combination of a member interposed between the valve stem and its opening means to deaden the sound of contact therebetween, and means axially slidably mounted on the valve stem to prevent displacement of said member.

3. In a device of the character described, the combination of a member interposed between the valve stem and its opening means to deaden the sound of contact therebetween, and means axially slidably mounted on the valve stem to prevent lateral displacement of said member.

4. In a device of the character described, the combination of a member loosely interposed between the valve stem and its opening, means to deaden the sound of contact therebetween, and means axially slidably mounted on the valve stem to prevent displacement of said member.

5. In a device of the character described, the combination with a valve and rocker arm, of a member interposed between the valve stem and rocker arm to deaden the sound of contact therebetween, means slidably mounted on the valve stem to prevent displacement of said member, and yielding means to hold said sliding means in contact with the rocker arm.

6. In a device of the character described, the combination with a valve and rocker arm, of a member interposed between the valve stem and rocker arm to deaden the sound of contact therebetween, means slidably mounted on the valve stem to prevent lateral displacement of said member, and yielding means to hold said sliding means in contact with the rocker arm.

7. In a device of the character described, the combination with a valve and rocker arm, of a member loosely interposed between the valve stem and rocker arm to deaden the sound of contact therebetween, means slidably mounted on the valve stem to prevent displacement of said member, and yielding means to hold said sliding means in contact with the rocker arm.

8. In a device of the character described, the combination with a valve and rocker arm, of a member loosely interposed between the valve stem and rocker arm to deaden the sound of contact therebetween, means slidably mounted on the valve stem to prevent lateral displacement of said member, and yielding means to hold said sliding means in contact with the rocker arm.

9. In a device of the character described, the combination with a valve and rocker

arm, of a member interposed between the valve stem and rocker arm to deaden the sound of contact therebetween, a sleeve member slidably mounted on the valve stem to prevent displacement of said member, and yielding means to hold said sleeve in contact with the rocker arm.

10. In a device of the character described, the combination with a valve and rocker arm, of a member interposed between the valve stem and rocker arm to deaden the sound of contact therebetween, said member being of substantially the same cross sectional area as the valve stem, a sleeve member slidably mounted on the valve stem to prevent lateral displacement of said member, and a spring to hold said sleeve in contact with the end of the rocker arm, said

spring being weaker than the valve spring.

11. In a device of the character described, 20 the combination with a valve and rocker arm, of a member interposed between the valve stem and rocker arm to deaden the sound of contact therebetween, said member being substantially the same cross sec- 25 tional area as the valve stem, a sleeve member slidably mounted on the valve stem to prevent lateral displacement of said member, and a spring mounted on the valve stem to hold said sleeve in contact with the end of 30 the rocker arm, said spring being weaker than the valve spring.

In witness that I claim the foregoing I have hereunto subscribed my name this 14th day of February, 1921.

GAIL BORDEN DOBSON.
